APPARATUS FOR OBTAINING AEROSOLS

Lucien Dautrebande, Washington, D. C., assignor
to Aerosol Corporation of America, New York,
N. Y., a corporation of Delaware

Application July 27, 1948, Serial No. 40,946

1 Claim. (Cl. 261—21)

1

This invention relates to methods and apparatus for obtaining improved aerosols of relatively high stability by obligatory filtration through a turbulent body of liquid and preferably "cracking" larger particles or clusters of particles, and especially to aerosols of a mean particle size or diameter of not over about 0.5 micron.

In aerosol therapy, it is very important to obtain aerosols of very low particle size if it is desired to have the aerosol penetrate to the innermost passages or zones in the lungs (alveoli). For this purpose, aerosols of not over 0.5 micron mean particle size are to be preferred, and in general the aerosols should be substantially free of particles of more than 1 micron diameter. The larger aerosol particles attract the smaller ones, they tend to deposit in the nasal and throat passages, and in some instances such deposit leads either to serious difficulties or to a lack of effectiveness of the substances dispersed.

In accordance with the invention, it has been found that aerosols of a mean particle size of not over 0.5 micron may be obtained readily by means of a convenient apparatus.

One of the objects of the invention is to produce improved aerosols having a mean particle size of not over 0.5 micron. Another object of the invention is the provision of apparatus for obtaining improved aerosols. Other objects of the invention will be apparent as details or embodiments of the invention are set forth herein-after.

In accordance with the invention, a liquid is dispersed by means of a compressed gas, such as air, to form a cloud of stable and unstable dispersed liquid particles in the gas, and the cloud is directed upwardly and passed into a turbulent body of liquid, then into a non-liquid zone; and preferably then into a jet energized by compressed air to crack aggregates of liquid particles, and then directed onto a baffle plate and then out of the aerosol generator. Generally, the aerosol resulting from the atomizing jet and the turbulent body of liquid has a mean particle size of 0.50 micron, whereas that resulting from the atomizing jet plus the turbulent body of liquid followed by the cracking jet has a mean particle size of 0.36 micron. This is true for an aqueous solution, regardless of the molecular weight or concentration of solute within usual concentration ranges suitable for aerosol therapy, e. g., 1 to 10% by weight of therapeutic agent.

Referring to the drawing, Figure 1 illustrates

2

an apparatus suitable for carrying out the method of the invention, partially in section and partially in elevation.

Figure 2 shows a cross-sectional view along the lines 2—2 of Figure 1.

The vessel 1 is provided with a liquid reservoir at the bottom, preferably detachably connected, e. g., by screw threads, for holding the liquid to be dispersed 5, a jet member made up of air inlet 10 3 and liquid supply tube 4 which extends into the liquid to be dispersed. A frusto-conical member 6 is provided directly over the aerosol generating zone 2. An optional skirt baffle member 10 may be suitably mounted within conical member 6, and in addition an optional screen or foraminous member 11 may be provided across the lower opening of the conical member. The upper or narrow end of member 6 may optionally fit into a jet member having an air inlet tube 3A. 20 A second frusto-conical member 7 is provided above the member 6 and extending completely across the vessel 1 so as to divide the latter into an upper zone and a lower zone. It is desirable to provide the member 7 with a series of small 25 openings or slits near the periphery thereof. The upper or narrow end of member 7 fits into a jet member, provided with air inlet tube 3B. Above this jet member, a baffle member 8 is provided, having openings or slits near the periphery thereof, to permit the aerosol to pass to exit 9, at the top of vessel 1.

Figure 2, a cross-sectional view along the lines 2—2 of Figure 1, shows the space, e. g., 2-3 mm. distance, between the upper edge surface of the optional cylindrical skirt member 10 and the conical member 6. It also shows three jet apertures in the jet assembly.

The total free area across the bottom of member 6 preferably equals the cross-sectional area of outlet member 9. The total cross-sectional area of the openings near the periphery of member 7, and also the total cross-sectional area of the openings in baffle member 8 each preferably equal the cross-sectional area of member 9. If 40 any one of these areas is smaller than the exit cross-sectional area above it, there will tend to be a positive pressure differential, impeding efficient operation of the jets. If any one of these areas is larger than the exit area, there will tend to 45 be poor efficiency in eliminating the larger size liquid particles. Generally, the diameter of exit member 9 is of the order of 1 to 3 cm., and the diameter of vessel 1 is about five times that of 50

member 9. The conical member 6 has a total angle at the maximum longitudinal section in the range of 30° to 50°, and the height of member 6 is of the order of 5 to 8 cm. The length of the skirt member 10 is of the order of $\frac{1}{4}$ to $\frac{1}{3}$ the height of member 6. Preferably, the distance between the upper edge of member 10 and member 6 is of the order of 1 to 3 mm. Generally, member 7 will be about the same height as member 6, but of a larger total angle, so as to reach across the complete cross-sectional area of vessel 1.

If desired, vessel 1 may be elongated, and provided with additional assemblies of frusto-conical members and jet assemblies similar to 7 and 3B, below baffle member 8. If desired, vessel 1 may be made up of sections, which may be joined by suitable means, e. g., by screw threads, each section having a frusto-conical member and an air inlet member similar to 7 and 3B, e. g., up to twelve such sections. Where there are several members similar to 7 and 3B, an aerosol outlet member, provided with a suitable valve, may be provided in the sidewall intermediate each of these conical and jet assembly members for taking off aerosols of desired mean particle size or of desired concentration of liquid particles in the gas.

If desired, the liquid reservoir in vessel 1 may have a conical shaped bottom, or be provided with a suitable feeding device for maintaining constant level of liquid therein, or it may be provided with means for continually removing liquid therefrom and replacing it with solution of controlled concentration. If desired, the liquid to be dispersed may be fed directly under pressure into tube 4, e. g., from an outside supply through suitable connections, not shown.

In operation, compressed air or other suitable gas is introduced into tube 3 under such conditions that liquid will be drawn up through tube 4 and dispersed in the form of a cloud or a mist at zone 2 and impelled upwardly into the member 6, no air or gas being introduced in tube 3A. Conditions are selected so that the cloud passing into member 6 contains a substantial amount of unstable liquid particles, which coalesce and form a very turbulent liquid body in the member 6. This liquid body is maintained in dynamic equilibrium, e. g., by balancing the amount of liquid supplied thereto against the amount running downward therefrom. In this turbulent liquid body, the larger and unstable liquid particles are removed from the cloud, and the resulting aerosol passed around the lower edge of member 6 and upward into member 7. Compressed air is introduced through tube 3B. This will draw the aerosol from within member 7 and form and direct a jet of aerosol against baffle member 8; and the resulting aerosol then passes through the openings in member 8 to the exit in member 9. A relatively small portion of the aerosol may pass through the apertures in member 7 and there may be a liquid film formed across the apertures in member 7, due to coalescence of relatively unstable liquid particles, and this film will tend to remove unstable particles from aerosol passing therethrough.

If desired, compressed air may be introduced through tube 3A, and this will enrich or increase the concentration of stable particles in the aerosol passing into member 7.

Member 7 serves to break up agglomerates of liquid particles which are not coalesced, and also

to reduce the mean particle size of the final aerosol.

Each of the jet members may have one, two or three sets of air and liquid apertures, three each being shown in the drawings. For example, the lower jet member may have one set of apertures and the upper jet member three sets, or vice-versa, or 2 by 2. Likewise, tube 3A may have three jets, tube 3B one, tube 3 two jets and so on. The variety of combinations of air-liquid mixtures is thus very large and adaptable to any therapeutic or industrial requirements.

In general, the size of the apertures is preferably such as to deliver a rate of air flow per aperture in the range of 15 to 25 liters per minute, for conventional relatively low air pressures of the order of 7 to 55 pounds per square inch gauge. For such an air flow, the rate of dispersion of liquid in the lower jet assembly is preferably in the range of 10 to 20 cc. per hour.

In a typical example of low particle size aerosols and their preparation, there is used an apparatus as illustrated in Figure 1, with only one set of air and liquid apertures in the lower jet assembly, and having three sets of apertures in the upper jet assembly, no air being introduced in inlet 3A, with a 10% aqueous solution of eosin in the liquid reservoir, an air input of 30 pounds per square inch on the upper and the lower jets, 3 and 3B. The resulting aerosols are passed into a chamber of 225 cubic meters capacity, the interior of which is maintained at atmospheric pressure. After 10 minutes, the aerosols are allowed to settle on collector plates, coated with a thin film of petrolatum, e. g., for an hour, then the plates are protected by a cover, cemented at the edges, e. g., with Duco cement, and immediately examined by means of an optical microscope, e. g., with oil immersion objective and 1125 magnification. The mean particle size of the aerosols is found to be 0.36 microns.

In another example, following the above procedure except without introducing any air into the upper jet member, 3B, the mean particle size of the resulting aerosol is 0.50 microns. This shows that the upper jet member substantially reduces the number of larger particles in the aerosol.

Aerosols of this mean particle size are obtained, using a gas inlet pressure in the range of 7 to 55 pounds per square inch gauge, aqueous solutions of materials of different molecular weights, or of different concentrations within suitable therapeutic concentration ranges, e. g., 1 to 10% by weight of the therapeutic agent.

If desired, the mean particle size may be determined by nephelometric methods or by electron microscope means. In the latter method, there are observed aerosol particles which are too small to be seen by means of the optical microscope, and when these are taken into consideration, the mean particle size of the aerosol will be even smaller, e. g., 0.07 microns for the first of the above examples as compared with 0.10 microns for the second as determined after collecting, freezing and drying.

It is known that aerosols of the size described have a tendency to form aggregates. In combating dust, these aggregates are very useful. In some cases, however, it is desirable to avoid aggregation of the dispersed particles, mainly for penetration into the respiratory depths of very powerful pharmacologic substances. The process of cracking not only reduces the particle size of the discrete micellae but also prevents the for-

mation of large aggregates. For instance, with the generator described, results obtained are summarized below:

Without cracking (i. e., without introducing air into member 3B):

General mean size	micron	0.1
Percentage of particles below 0.1 micron	per cent	81.1
Mean size of particles below 0.1 micron	Angstrom U.	566
Mean size of particles above 0.1 micron	micron	0.30
Mean size of optically visible aggregates	micron	2.1
Largest single particle	do	1.4
Largest aggregate	do	4.3

With cracking:

General mean size	micron	0.07
Percentage of particles below 0.1 micron	per cent	84.0
Mean size of particles below 0.1 micron	Angstrom U.	425
Mean size of particles above 0.1 micron	micron	0.20
Mean size of optically visible aggregates	micron	0.64
Largest single particle	do	0.6
Largest aggregate	do	1.2

This process thus permits not only the production of smaller micellae but also considerable reduction in the size of the aggregates.

Using a lower nozzle with one jet and an upper nozzle with three jets and with an air pressure in both nozzles of 42.5 pounds per square inch gauge, the following results are obtained:

Percentage of particles below 1 micron	per cent	100
Percentage of particles below 100 Angstroms	per cent	90
Mean general size of individual particles	Angstroms	446
Mean size of particles below 1000 Angstroms	Angstroms	281
Mean size of particles above 1000 Angstroms	Angstroms	1,630
Largest single particle	do	3,150

This aerosol contains not a single aggregate and the micellary size is strikingly low and uniform.

The apparatus or parts thereof may be made of glass, metal, plastic, or the like suitable material; and although various members are described as being substantially circular in cross section, other shapes may be used provided the critical relationships disclosed are retained.

The particular jet members discussed above are admirably adapted for producing aerosols. However, known types of jet members may be used, providing the resulting mist or cloud contains both very fine liquid particles and also a substantial amount of larger relatively unstable particles. The unstable particles will tend to be removed in the turbulent liquid body or in the treatments subsequent to contact with the turbulent body, or both.

The existence and maintenance of the turbulent liquid body is of great importance in carrying out my invention as disclosed herein. I have found that the formation and utilization of one

or more turbulent liquid masses is critical in the production of aerosols of the preferred small size and uniformity. This may be due to the myriad of liquid films comprising the turbulent mass which are available to act upon the aerosols as they pass through the apparatus.

The relatively uniform aerosols of very low mean particle size, having substantially all particles of less than 1 micron maximum size, are particularly suitable for use in aerosol therapy, particularly in the treatment of the innermost passages or regions (alveoli) in the lungs. If it is desired to simultaneously treat or medicate the nasal or throat passages, larger mean particle size aerosols, having some particles of the order of 1 to 5 microns diameter, may be used.

The aerosols produced in accordance with the invention may be suitable for other uses, e. g., precipitation or agglutination of very fine dust particles, which dust particles are so fine that they pass through a liquid layer, through the nasal and throat passages, and into the innermost regions of the lungs where they may deposit and produce very undesirable effects, e. g., silicosis. The very fine aerosol particles tend to agglomerate and coalesce with the very fine dust particles, to produce larger size particles which may be precipitated or settled.

In view of the foregoing disclosures, variations and modifications thereof will be apparent to those skilled in the art, and all such variations and modifications are broadly contemplated within the invention.

I claim:

35 In an apparatus for producing an improved aerosol, a vessel provided with a liquid reservoir, atomizing means comprising a liquid feed tube in communication with the said reservoir and an upwardly directed air inlet tube, a first frusto-conical member set axially about vertically above said atomizing means, a skirt baffle member within said first frusto-conical member, a fine meshed screen across the larger end of said first frusto-conical member, a second and larger frusto-conical member set above said first member and dividing said vessel into an upper and a lower zone, said second member being apertured near the periphery thereof, the narrow end of said second member communicating with a second atomizing means, a baffle member set above said second atomizing means, and an aerosol outlet tube.
